UNITED STATES PATENT OFFICE

151,209

DESIGN FOR A COMBINED HOLDER AND CONTAINERS FOR PERFUMERY

Georges Baud, Paris, France

Application March 29, 1946, Serial No. 128,048

Term of patent 14 years

(Cl. D80—5)

To all whom it may concern:

Be it known that I, Georges Baud, a citizen of France, residing in Paris, France, have invented a new, original, and ornamental Design for a Combined Holder and Containers for Perfumery, of which the following is a specification, reference being had to the accompanying drawing, forming part thereof.

Fig. 1 is a front perspective view of the combined holder and containers for perfumery in closed position, showing my new design;

Fig. 2 is a perspective view thereof in open position.

The back of the container is ornamented by stripes which continue the stripes shown on the front and top thereof.

I claim:

The ornamental design for a combined holder and containers for perfumery, as shown and described.

G. BAUD.
